UNITED STATES PATENT OFFICE.

CHARLES M. JOHNSON, OF AVALON, PENNSYLVANIA.

BUNSEN BURNER.

1,342,912.

Specification of Letters Patent.

Patented June 8, 1920.

Application filed August 7, 1919. Serial No. 315,810.

To all whom it may concern:

Be it known that I, CHARLES M. JOHNSON, residing at Avalon, in the county of Allegheny and State of Pennsylvania, a citizen of the United States, have invented or discovered certain new and useful Improvement in Bunsen Burners, of which improvement the following is a specification.

10 My invention relates to improvements in the construction of Bunsen burners, and more particularly of burners of the type commonly known as Chaddock burners. These Chaddock burners are made of earthenware, and consist of two parts or members, a base member and a top member, separable and replaceable the one with respect to the other. They are extensively used in metallurgical laboratories, where 20 relatively high and widely-ranging temperatures are required. My invention is not limited in the matter of material, but earthenware has its practical advantages for such use as I have indicated; and, in the field 25 of earthenware, I preferably employ a mixture of good refractory plastic clay and zirconium oxid. This mixture is one which I have developed and perfected; it forms no part of my present invention; and here 30 it will suffice to say that in such mixture the zirconium oxid content may advantageously in size equal or exceed the clay content.

The burner of my invention is illustrated in the accompanying drawings, of which 35 Figure 1 is a view in side elevation of the base member alone; Fig. 2 is a like view of the base member with one of a plurality of top members applied to it; Fig. 3 is a like view of the base member with another of 40 the plurality of top members applied to it; Fig. 4 is a like view of the three members shown in Figs. 1, 2, and 3, assembled in one arrangement; Fig. 5 a like view of the same three members assembled in another arrangement; while Figs. 6 and 7 are views 45 in central vertical section of the burner parts assembled in Figs. 4 and 5.

The burner consists essentially of three parts or members; a base member, 1, and 50 two top members, 2 and 3. The base member is provided with the usual central vertical gas duct 4 (Figs. 6 and 7) to which gas has entrance through the lateral duct 5. An air duct 6 also (one or more may be 55 provided) is formed in the base. The base member terminates above in an extremity 7

of reduced diameter, to form a seat for the top members; applied alternately. This extremity 7 is provided with one or more air-admitting notches 8. While improved in 60 design, this base member is, in its essential features, the base member of the Chaddock burner mentioned above.

The two top members are so far identical that each is of circular cross section, is 65 provided with a flaring interior duct or chamber open through the member as shown, and is adapted to be seated by its smaller end upon the upper extremity of the base member 1, as shown in Figs. 2-7. Either 70 top member when so applied forms, with the notches 8 of the base member, air ducts which lead into the combustion chamber, which the upwardly enlarging duct in the top constitutes, when the top member is so 75 applied. As thus far described, the new feature is the plurality of top members; otherwise, the structure is in essential features that of the Chaddock burner.

The burner so assembled, by the application of one of the said top members, as shown in Figs. 2, 3, is for some kinds of service complete. The gas burns in the flaring duct or chamber in the top, and this chamber then becomes indeed a reverberatory chamber of heat-confining material, to bring to relatively high temperature a crucible or other article resting within or upon 80 said top member. The larger rim of one or both of these top members may be 85 toothed, as shown in Fig. 3, to permit the free play of flame upon an article resting on its rim.

The two tops are so related in the size of their larger rims that one may rest upon the 95 other, as shown in Fig. 4. When so arranged, the chambers within the two tops coöperate to form a muffle or reverberatory furnace chamber with a chimney above, within which articles may be subjected to 100 high and steady temperatures for relatively long periods.

Again, the two tops may be assembled one with another and both with respect to the base member, as shown in Fig. 5, in which 105 arrangement the uppermost part may constitute a separable carrier for the article undergoing heat treatment; it sometimes is a convenience to so increase the height of the burner.

It is possible, by forming coöoperating notches in the smaller rim of the top mem-

ber, as indicated at 9 in Fig. 5, to vary (by turning the top member upon its seat in the bottom member) the size of the air ducts opening to the chamber within the burner top, and so control the combustion and correspondingly the intensity of the flame,—or to vary the air supply to suit variations in rate or quality of the gas supply.

I claim as my invention:

- 10 1. In a Bunsen burner, the combination, with a base member having a central gas duct, and a seat for a top member at its upper extremity, said seat being provided with an external notch, of two top members; each 15 of said top members being of circular cross section and provided with a widening central passageway or chamber, each adapted to be applied at its narrow end to, and to be borne upon, the seat formed in said base member, as aforesaid, and to constitute with the notches therein air ports opening into the chamber within, the said burner serving complete with one or the other of said tops, or with both, the second of said tops when 25 employed being applicable in alternate positions to the first, to constitute with said first top either a muffle, or a support for an article to be heated, substantially as described.
- 20 2. In a Bunsen burner, the combination, with a base member having a central gas duct and a seat for a top member at its upper extremity, of two top members, each of 25 said top members being of circular cross section and provided with a widening central

passageway or chamber, each adapted to be applied at its narrower end to, and to be borne upon, the seat formed in said base member, as aforesaid, and the one adapted to be seated by its wider end in the wider 40 end of the other, substantially as described.

3. In a Bunsen burner, the combination, with a base member having a central upward-opening gas duct and notched externally at its upper end, of a top member of 45 circular cross section and provided with a widening central passageway or chamber, the said top member adapted to be seated by its narrower end upon the upper extremity of said base member and adapted to rotate 50 upon said base member when so seated, and said top member being notched at such narrower end, substantially as described.

4. A Bunsen burner, including a body having a base, a central gas duct, and a flaring top, and a removable top member of circular cross section provided with a widening central passageway or chamber and applicable to the flaring top of the burner in either of two alternate positions, and when applied constituting together with such flaring top either a muffle or a support for an article to be heated, substantially as described.

In testimony whereof I have hereunto set 65 my hand.

CHARLES M. JOHNSON
